[57] CLAIM

The ornamental design of a container or similar article,
as shown and described.

DESCRIPTION

FIG. 1 is a top plan view of a container or similar article
showing my design;

FIG. 2 is a side elevation of one side of the container, it
being understood that the opposite side is a mirror
image of that illustrated;

FIG. 3 is a bottom view of the container;

FIG. 4 is an end elevation of one end of the container;
and

FIG. 5 is an end elevation of the opposite end of the
container.

FIG.1
